COMPENSATOR FOR AUTOMATIC SCALES

Howland F. Briggs, Buffalo, N. Y., assignor to
 Consolidated Packaging Machinery Corporation, Buffalo, N. Y., a corporation of New York

Application June 14, 1940, Serial No. 340,457

13 Claims. (Cl. 265—60)

This invention relates to new and useful improvements in scale compensating devices and particularly seeks to provide novel compensating means for use in conjunction with automatic weighing scales and which can be adjusted from a position remote from the scale.

In the use of automatic scales in the weighing of grain or mixed feeds, much difficulty has been encountered in fluctuation of the final weight of the mass weighed due to the variable condition of the dribble stream after final cut-off when materials of varying densities are weighed. Therefore it is necessary to provide the scales with compensating means by which the effect of density variations in the weighing of different materials will not vary the final weight.

Two general classes of scale compensators, manual and automatic or self-acting, have been devised in an effort to solve this problem. Of these two general classes of compensators, the manual type is impractical for use in conjunction with scale installations for the weighing of grain, since any adjustments to the compensator must be made by climbing up onto the scale and then effecting the adjustment. Also, with this type of compensator each separate adjustment must be checked by a series of test weighings in order to assure accuracy, thereby causing a material loss of time in the actual weighing operations of a production run.

The automatic or self-acting type of compensator is also subject to certain objections. The self-acting types are generally actuated partly as the result of impact of the stream of falling material, and accuracy thereof will be obviously affected by variations of the falling stream due to changes in the densities of the materials being weighed. The self-acting types are still part of the actual weighing mechanism and accordingly must therefore be readjusted between changes from one material to another, particularly those which vary a great deal in density.

Therefore an object of this invention is to provide a compensator for use on automatic weighing scales which can be readily regulated to compensate for variations in density in the weighing of different materials.

Another object of the invention is to provide a device of the character stated in which the compensating adjustments are effected by control devices located at a position convenient to the operator and remote from the scale.

Another object of the invention is to provide a device of the character stated in which the

control or adjusting means therefor is provided with suitable indicia by which the proper adjustment for a particular material being weighed may be determined or indicated.

5 Another object of the invention is to provide a device of the character stated which includes a chain having one end dependably fastened to the counterweight of the scale and means connected to the other end of the chain for varying the effective weight of the depending portion of the chain.

Another object of the invention is to provide a device of the character stated in which the means for varying the effective weight of the chain includes a housing into which one end of the chain is inserted, and devices associated with the housing and connected to the chain end contained therein for changing the position of the chain end within the housing to thereby vary the length and effective weight of chain without the housing for compensating purposes.

Another object of the invention is to provide a device of the character stated which is simple in design, rugged in construction, and economical to manufacture.

With these and other objects in view, the nature of which will become more apparent, the invention will be more fully understood by reference to the drawings, the accompanying detailed description, and the appended claims.

In the drawings:

Fig. 1 is a front elevation of one type of scale with which a compensating device constructed in accordance with this invention may be employed;

Fig. 2 is a side elevation thereof;

Fig. 3 is a somewhat diagrammatic front elevation of a combined weighing, filling and closing machine of the type adapted for handling grain and to which compensating devices constructed in accordance with the invention are applied;

Fig. 4 is a fragmentary, somewhat diagrammatic plan view of the machine illustrated in Fig. 3 and showing the relative arrangement of the multiple scales;

Fig. 5 is an enlarged elevation, partly in section, of the compensator assembly;

Fig. 6 is a horizontal section taken on line 6—6 of Fig. 5;

Fig. 7 is a detail front elevation of the actuating handles and indicating dial;

Fig. 8 is a horizontal section taken on line 8—8 of Fig. 5, parts of the actuating handles being shown in section;

Fig. 9 is a front elevation of a modified form of chain actuator;

Fig. 10 is a side elevation of the actuator illustrated in Fig. 9;

Fig. 11 is a somewhat diagrammatic view, partly in section, showing a modified form of actuating mechanism in which the chain is moved positively through the medium of gear connections;

Fig. 12 is a vertical section taken on line 12—12 of Fig. 11;

Fig. 13 is a front elevation of a multiple unit control panel which may be used in conjunction with a machine of the type disclosed in Fig. 3;

Fig. 14 is a horizontal section taken on line 14—14 of Fig. 13;

Fig. 15 is a vertical section taken on line 15—15 of Fig. 13;

Fig. 16 is a somewhat diagrammatic front elevation of a chain and sprocket actuating means which may be used in place of the gear train illustrated in Fig. 11.

The compensating device forming the basis of the present invention may be used in conjunction with automatic weighing scales somewhat diagrammatically indicated in Figs. 1 and 2 of the drawings, and of the general type fully described in United States Letters Patent No. 855,578 issued to G. Hoepner June 4, 1907, although it is of course to be understood that the compensator could be applied to other types of automatic scales equally as well. Automatic scales of this type include a main frame 5 supporting a supply hopper generally indicated at 6, and a discharge chute generally indicated at 7. A weigh bucket 8 is interposed between the supply hopper 6 and the discharge chute 7 and is fulcrumed as at 9 on one end of a main weigh beam 10 which is fulcrumed on the frame at 11. The other end of the weigh beam carries the usual counter-balancing weights generally indicated at 12. For the purposes of fine adjustment when the scale is first set up, the weigh beam 10 may be provided with relatively small counterweights 13 slidably mounted thereon.

In the operation of scales of this type the flow of material to be weighed into the weigh bucket is divided into three phases, namely, a main charge, a dribble stream and the stream in air which remains after final cut off. By way of example it may be assumed that a scale installation designed for use in weighing a number of materials of varying densities is initially adjusted to properly weigh the most dense of these materials. In making the adjustments as is well known to those skilled in the art, a scale is set for a predetermined weight or total charge. When the scale is set into operation the main charge is permitted to enter the weigh bucket and the main supply gate is closed off by the usual mechanisms for that purpose, then the dribble stream continues to flow into the weigh bucket until the total weight of a charge is almost reached when the dribble gate is closed. The specific construction and operation of the main supply and the dribble gate forms no part of the present invention, but is clearly described and illustrated in the above referred to patent. At the instant of closing the dribble gate there is still a stream of material in the air between the dribble gate and the weigh bucket which enters the weigh bucket to complete the aggregate weight of the charge.

If the scale installation is now used to weigh a less dense material but retaining the same scale adjustments, it will be apparent that the weight of the charge in the weigh bucket will be the same

at the time of final cut-off of the dribble stream as it was with the more dense material, but the weight of the stream in the air will be less since the material being weighed is less dense. Therefore, the complete charge including the weight of the stream in the air will be underweight. Thus it is apparent that in order to use the scale for weighing operations on less dense materials than that for which the scale was initially set, it is necessary to readjust the scale by adding to the counterweight on the weigh beam to effect an increase in the charge in the weigh bucket at the time of final cut-off so that the weight of the charge will be greater and the weight of the charge including a stream in air will be at the proper value. In other words it is obvious that by adding the proper amount of weight to the weigh beam the charge plus the stream in air can be made to again equal the desired final weight. The compensating device constructed in accordance with the principles of this invention has been designed to facilitate the scale adjustments necessary in changing the scale operation from a relatively dense material to a relatively lighter material or vice versa.

In Figs. 5 to 8 of the drawings there is illustrated a preferred form of compensating device which may be used in conjunction with the main counterweight of an automatic scale of the type indicated. In this device a cable chain 14 has one end freely and dependably attached to the lower end of the main counterweight 12. The other end of the chain 14 is retained within a generally vertically disposed housing 15 secured to the main frame through the medium of appropriate supports generally indicated at 16. The upper end of the housing 15 is provided with a semi-circular hood portion 17 containing a semi-cylindrical horn element 18, the arcuate surface of which may be highly polished and over which the chain 14 is adapted to slide. The end of chain 14 which is retained within the housing 15 is secured to the upper end of a connecting bar 19 freely slidable within the housing. The bar 19 is adapted to be pulled downwardly through the medium of chain or cable connections 20, one end of which is connected to the bar and the other end of which is connected to a reel assembly generally indicated at 21 through the medium of a conduit 21A.

The actuating assembly 21 includes a housing 22 having a front cover or dial plate 23 and a centrally disposed stud 24 having a flanged base 24a rigidly secured to the rear wall thereof and projecting forwardly through the middle of the dial plate 23. A reel or drum 25 around which the actuating chain or cable 20 is wound is mounted on the stud 24 and is freely rotatable thereon. The reel 25 is adapted to be rotated through the medium of an actuating handle 26 connected thereto through the medium of pin connections 27 and is freely rotatable on the stud 24. It should be noted that the forwardly projecting end of the stud 24 is provided with a threaded portion generally indicated at 28 which is adapted to be engaged by a locking handle or element 29. Thus when the handle or locking element 29 is engaged on the threaded end of the stud it will abut the forward face of the actuating handle 26 and cause the handle of the reel 25 connected thereto to move rearwardly so that the rear face of the reel will be forced against the face of the flange 24a of the stud and will be retained thereagainst in locked position.

In order that the weight of that portion of

the chain 14 which is retained within the housing 15 will not cause the chain to gravitate downwardly within the housing and thus retract the chain therein, a spring motor 31 including a coil spring 32 is secured to the housing 15 and the free end of the spring 32 is carried downwardly within the casing 15 and is secured to the connecting bar 19. Thus it will be apparent that when the locking element 29 of the actuating assembly is released, the spring motor 31 becomes effective to raise the connecting bar 19, unreel actuating cable from the reel 25, and effect an upward movement of the chain 14 within the housing 15 and a projection of the chain from the hood portion 17 thereof, thus providing a pendant loop of chain without the housing. It will also be apparent that as more of the chain 14 is projected from the hood 17 more links are dependably added to the main counterweight 12 with the consequent increase of the weight thereon.

For convenience in determining the exact amount of projection or retraction of the links of the chain 14 from the hood 17, the plate 23 of the reel assembly 21 may be provided with a plurality of indicia 33 with which an indicator 34 carried by the actuating handle 26 is adapted to register.

In Figs. 9 and 10 of the drawings there is illustrated a modified form of actuating assembly which may be employed with the compensating device above described. This form of actuating device includes a generally rectangular housing 35 which may be connected to the cable conduit 21A in place of the reel assembly 21. The housing 35 is adapted to slidably support a rack element 36 connected to the lower end of the actuating cable or chain 20 and which carries an indicating finger 37 extending through a slot generally indicated at 38 formed in one face of the housing 35. The indicator 37 is adapted to register with a plurality of scale graduations indicated at 39. The rack 36 is adapted to be reciprocated within the housing 35 through the medium of a pinion 40 meshing therewith and fixed to a shaft 41 rotatably mounted on the housing 35. An actuating handle 42 is secured to one end of the pinion shaft 41. Thus as the actuating handle 42 is turned in one direction the rack will be raised and consequently chain will be projected from the hood 17 of the main chain housing 15, and when the wheel 42 is rotated in the opposite direction the rack will be lowered and the chain 14 will be retracted into the hood 17 and the chain housing 15.

A modified form of compensator which employs positive actuating connections for increasing or decreasing the length of the pendant chain is illustrated in Figs. 11 and 12 of the drawings. In this particular structure a sprocket chain 43 of the silent mesh type is carried by and over a sprocket gear 44 secured to one end of a shaft 45 journaled in a gear housing generally indicated at 46. The inner end of the shaft 45 projects into the gear housing and is provided with a bevelled gear 47 rigidly secured thereto. The bevelled gear 47 meshes with a complementary bevelled gear 48 rigidly secured to a vertical shaft 49, the upper end of which is journaled in the housing 45 and the lower end of which is journaled in a lower gear housing 50 located at a position convenient to the operator. The gear housing 50 contains a bevelled gear 51 rigidly secured to the lower end of the shaft 49 and a complementary meshing bevelled gear 52 freely

rotatable on a flanged stud 53 rigidly secured to the housing 50. Actuating and locking handles 54 and 55 respectively are carried by the stud 53 and function in the same manner as the handles 26 and 29 of the actuating mechanism previously described, to rotate the bevelled gears 51 and 52, the shaft 49, the bevelled gears 47 and 48 and consequently the sprocket gear 44. It will be readily apparent that rotation of the sprocket gear 44 with the chain 43 meshed therewith will effect a lengthening or shortening of the pendant loop of the chain 43. The free end of the chain 43 may be provided with a weight 56 which serves to positively maintain the chain in engagement with the sprocket gear 44. A housing 57 may be provided to shield or cover the sprocket 44 and its associated chain. Thus the lengthening or shortening of the pendant loop of the chain 43 may be positively effected through the medium of the above described gear and shaft connections.

A main control unit from which a plurality of compensating devices may be actuated from a single operating station is illustrated in Figs. 13 to 15 of the drawings. This control unit may be a fabricated panel assembly which includes a control box generally indicated at 57 which comprises a rear wall portion 58 formed from sheet metal and a front wall portion generally indicated at 59 which is comprised of a plurality of separated panel portions 60 maintained in spaced relation from a rear wall 58 through the medium of bolts 61 and spacer elements 62 disposed intermediate said front and rear wall portions. The spaces between each of the front panel sections 60 define slots 63 respectively adapted to receive slide assemblies generally indicated at 64. Each slide assembly 64 comprises male and female clamping elements 65 and 66, the male element 65 being disposed in back of the front wall 59 and the female element being disposed in front of the male element 65. The male element carries a forwardly projecting stud 67 upon which is threadably engaged a clamping or locking handle 68, the inner end of which is adapted to abut against the female clamping element 66 to thereby press the female element rearwardly against the front face of the wall 59 and draw the male element forwardly against the rear face of the wall 59 to thereby releasably secure the slide assembly in fixed position.

The upper end of the panel assembly generally indicated at 57 is adapted to be closed through the medium of a longitudinally extending cap member 69 secured thereto. The individual conduits 21A of the respective compensator devices with which the control panel is to be associated have their free ends secured to the cap member 69 and are disposed in vertical alignment with the slide assemblies 64. The actuating chains 20 which extend through the respective conduits 21A are thereby allowed to drop downwardly into the control panel and have their ends respectively secured to the respective slide assemblies 64 through the medium of set screws 70.

Thus it is apparent that the scale units of a combined weighing, filling and closing machine of the type generally illustrated in Figs. 3 and 4 of the drawings may be adjusted from a point convenient to the operator through the medium of a multiple unit control panel of the type above described. It is obvious that in order to effect the compensating adjustments on the individual scales through the use of this control panel, it is only necessary to release the slide assemblies

64 by twisting the handles 63 thereof and then moving the respective slides either upwardly or downwardly to increase or decrease the length of the pendant compensating chain.

Each slide assembly 64 may be provided with an indicating finger 71 adapted to register with scale graduations generally indicated at 72 which are formed adjacent one side of each of the slots 63 to thereby provide positive indication or determination of the amount of compensation effected through movement of the respective slide assemblies.

In Fig. 16 of the drawings there is illustrated a modified form of compensating chain actuating device which may be used in place of the gear and shaft actuating connections illustrated in Figs. 11 and 12. In this particular form the inner end of the shaft 45 may be provided with a second sprocket gear 73 with which is engaged an endless sprocket chain 74. The other loop portion of the sprocket chain 74 may be engaged by a lower sprocket gear 75 located at a position convenient to the operator. The sprocket gear 75 may carry an indicating dial 76 having a plurality of indicia 77 formed thereon which are adapted to register with an indicating finger 78 secured to the frame in any manner desired.

Thus it will be seen that the herein described invention provides a novel compensating device for use on automatic weighing scales; in which the compensating adjustments are effective by control devices located at a position convenient to the operator and remote from the scale; in which the compensating device includes a chain having one end dependably fastened to the main scale counterweight and means connected to the other end of the chain for varying the effective weight of the depending portion of the chain and which is simple in design, rugged in construction and economical to manufacture.

It is of course to be understood that certain details of arrangement and proportions of parts may be variously modified without exceeding the scope of the appended claims.

I claim:

1. In a weighing scale wherein is provided a frame, a weigh beam fulcrumed on said frame, a weigh bucket fulcrumed on one end of said weigh beam, and a counterweight pivotally carried by the other end of said weigh beam; means for varying the effective weight of said counterweight and including a relatively long flexible weighing element having one end dependably fastened to said counterweight, means carried by said frame for supporting said flexible element in a pendant loop and for varying the length of said pendant loop, said last named means including a vertically disposed housing adapted to receive the end of said flexible element and having an arcuate supporting surface provided at the upper end thereof and over which said flexible element is adapted to ride, and actuating devices associated with said housing for adjusting the position of that end of the flexible element retained therein to thereby effect a change in length of said pendant loop.

2. In a weighing scale wherein is provided a frame, a weigh beam fulcrumed on said frame, a weigh bucket fulcrumed on one end of said weigh beam, and a counterweight pivotally carried by the other end of said weigh beam; means for varying the effective weight of said counterweight and including a relatively long flexible weighing chain having one end dependably fastened to said counterweight, means carried by said frame

for supporting said chain in a pendant loop and for varying the length of said pendant loop, said last named means including a vertically disposed housing adapted to receive the end of said chain and having an arcuate supporting surface provided at the upper end thereof and over which said chain is adapted to ride, means carried by said housing and connected with that end of the chain retained therein for lifting said chain and propelling a portion thereof from said housing to increase the length of said pendant loop, and actuating devices associated with said housing for controlling the position of said chain under the influence of said lifting means and for retracting a portion of said chain into said housing to decrease the length of said pendant chain.

3. In a weighing scale wherein is provided a frame, a weigh beam fulcrumed on said frame, a weigh bucket fulcrumed on one end of said weigh beam, and a counterweight pivotally carried by the other end of said weigh beam; means for varying the effective weight of said counterweight and including a relatively long flexible weighing chain having one end dependably fastened to said counterweight, means carried by said frame for supporting said chain in a pendant loop and for varying the length of said pendant loop, said last named means including a vertically disposed housing adapted to receive the end of said chain and having an arcuate supporting surface provided at the upper end thereof and over which said chain is adapted to ride, means carried by said housing and connected with that end of the chain retained therein for lifting said chain and propelling a portion thereof from said housing to increase the length of said pendant loop, and actuating devices associated with said housing for controlling the position of said chain under the influence of said lifting means and for retracting a portion of said chain into said housing to decrease the length of said pendant chain.

4. In a weighing scale wherein is provided a

frame, a weigh beam fulcrumed on said frame, a weigh bucket fulcrumed on one end of said weigh beam, and a counterweight pivotally carried by the other end of said weigh beam; means for varying the effective weight of said counterweight and including a relatively long flexible weighing chain having one end dependably fastened to said counterweight, means carried by said frame for supporting said chain in a pendant loop and for varying the length of said pendant loop, said last named means including a vertically disposed housing adapted to receive the end of said chain and having an arcuate supporting surface provided at the upper end thereof and over which said chain is adapted to ride, means carried by said housing and connected with that end of the chain retained therein for lifting said chain and propelling a portion thereof from said housing to increase the length of said pendant loop, and actuating devices associated with said housing for controlling the position of said chain under the influence of said lifting means and for retracting a portion of said chain into said housing to decrease the length of said pendant chain, said actuating devices comprising a reel rotatably mounted within said reel housing, flexible connecting means joining said chain and said reel through said conduit, and means for rotating said reel.

connected to said chain housing through the medium of a conduit, a reel rotatably mounted within said reel housing, flexible connecting means joining said chain and said reel through said conduit, means for rotating said reel, and means to lock said reel in fixed position.

5. In a weighing scale wherein is provided a frame, a weigh beam fulcrumed on said frame, a weigh bucket fulcrumed on one end of said weigh beam, and a counterweight pivotally carried by the other end of said weigh beam; means for varying the effective weight of said counterweight and including a relatively long flexible weighing chain having one end dependably fastened to said counterweight, means carried by said frame for supporting said chain in a pendant loop and for varying the length of said pendant loop, said last named means including a vertically disposed housing adapted to receive the end of said chain and having an arcuate supporting surface provided at the upper end thereof and over which said chain is adapted to ride, means carried by said housing and connected with that end of the chain retained therein for lifting said chain and propelling a portion thereof from said housing to increase the length of said pendant loop, and actuating devices associated with said housing for controlling the position of said chain under the influence of said lifting means and for retracting a portion of said chain into said housing to decrease the length of said pendant chain, said actuating devices comprising a reel housing secured to said frame at a position remote from said counterweight and connected to said chain housing through the medium of a conduit, a reel rotatably mounted within said reel housing, flexible connecting means joining said chain and said reel through said conduit, and means for rotating said reel.

6. In a weighing scale wherein is provided a frame, a weigh beam fulcrumed on said frame, a weigh bucket fulcrumed on one end of said weigh beam, and a counterweight pivotally carried by the other end of said weigh beam; means for varying the effective weight of said counterweight and including a relatively long flexible weighing chain having one end dependably fastened to said counterweight, means carried by said frame for supporting said chain in a pendant loop and for varying the length of said pendant loop, said last named means including a vertically disposed housing adapted to receive the end of said chain and having an arcuate supporting surface provided at the upper end thereof and over which said chain is adapted to ride, means carried by said housing and connected with that end of the chain retained therein for lifting said chain and propelling a portion thereof from said housing to increase the length of said pendant loop, and actuating devices associated with said housing for controlling the position of said chain under the influence of said lifting means and for retracting a portion of said chain into said housing to decrease the length of said pendant chain, said actuating devices comprising a slide housing secured to said frame and connected to said chain housing through the medium of a conduit, a slide member slidably mounted within said slide housing, flexible connecting means joining said chain and said slide member through said conduit, and means for reciprocating said slide.

7. In a weighing scale wherein is provided a frame, a weigh beam fulcrumed on said frame, a weigh bucket fulcrumed on one end of said

weigh beam, and a counterweight pivotally carried by the other end of said weigh beam; means for varying the effective weight of said counterweight and including a relatively long flexible weighing chain having one end dependably fastened to said counterweight, means carried by said frame for supporting said chain in a pendant loop and for varying the length of said pendant loop, said last named means including a vertically disposed housing adapted to receive the end of said chain and having an arcuate supporting surface provided at the upper end thereof and over which said chain is adapted to ride, means carried by said housing and connected with that end of the chain retained therein for lifting said chain and propelling a portion thereof from said housing to increase the length of said pendant loop, and actuating devices associated with said housing for controlling the position of said chain under the influence of said lifting means and for retracting a portion of said chain into said housing to decrease the length of said pendant chain, said actuating devices comprising a slide housing secured to said frame and connected to said chain housing through the medium of a conduit, a slide member slidably mounted within said slide housing, flexible connecting means joining said chain and said slide member through said conduit, and means including rack and pinion connections for reciprocating said slide.

8. In a weighing scale wherein is provided a frame, a weigh beam fulcrumed on said frame, a weigh bucket fulcrumed on one end of said weigh beam, and a counterweight pivotally carried by the other end of said weigh beam; means for varying the effective weight of said counterweight and including a relatively long flexible weighing chain having one end dependably fastened to said counterweight, means carried by said frame for supporting said chain in a pendant loop and for varying the length of said pendant loop, said last named means including a vertically disposed housing adapted to receive the end of said chain and having an arcuate supporting surface provided at the upper end thereof and over which said chain is adapted to ride, means carried by said housing and connected with that end of the chain retained therein for lifting said chain and propelling a portion thereof from said housing to increase the length of said pendant loop, and actuating devices associated with said housing for controlling the position of said chain under the influence of said lifting means and for retracting a portion of said chain into said housing to decrease the length of said pendant chain, said actuating devices comprising a slide housing secured to said frame and connected to said chain housing through the medium of a conduit, said housing being provided with a longitudinally disposed slot, scale graduations disposed adjacent said slot, a slide member slidably mounted within said slide housing, an indicating finger carried by said slide and projecting through the slot formed in said housing disposed in cooperative relation to said scale graduations, flexible connecting means joining said chain and said slide member through said conduit, and means for reciprocating said slide.

9. In a weighing scale wherein is provided a frame, a weigh beam fulcrumed on said frame, a weigh bucket fulcrumed on one end of said weigh beam, and a counterweight pivotally carried by the other end of said weigh beam; means for varying the effective weight of said

counterweight and including a relatively long flexible weighing chain having one end dependably fastened to said counterweight, means carried by said frame for supporting said chain in a pendant loop and for varying the length of said pendant loop, said last named means including a vertically disposed housing adapted to receive the end of said chain and having an arcuate supporting surface provided at the upper end thereof and over which said chain is adapted to ride, means carried by said housing and connected with that end of the chain retained therein for lifting said chain and propelling a portion thereof from said housing to increase the length of said pendant loop, and actuating devices associated with said housing for controlling the position of said chain under the influence of said lifting means and for retracting a portion of said chain into said housing to decrease the length of said pendant chain, said actuating devices comprising a slide housing secured to said frame and connected to said chain housing through the medium of a conduit, said housing being provided with a longitudinally disposed slot, scale graduations disposed adjacent said slot, a slide member slidably mounted within said slide housing, an indicating finger carried by said slide and projecting through the slot formed in said housing disposed in cooperative relation to said scale graduations, flexible connecting means joining said chain and said slide member through said conduit, and means including rack and pinion connections for reciprocating said slide.

10. In a weighing scale wherein is provided a frame, a weigh beam fulcrumed on said frame, a weigh bucket fulcrumed on one end of said weigh beam, and a counterweight pivotally carried by the other end of said weigh beam; means for varying the effective weight of said counterweight and including a relatively long flexible weighing chain having one end dependably fastened to said counterweight, means for supporting said chain in a pendant loop and for varying the length of said pendant loop, said last named means including a vertically disposed housing adapted to receive the other end of said chain and having a sprocket gear engageable with said chain and journaled adjacent the upper end thereof, and means for imparting a movement of rotation to said sprocket gear to thereby propel the chain from said housing or to retract the chain into said housing and vary the length of the pendant loop thereof.

11. In a weighing scale wherein is provided a frame, a weigh beam fulcrumed on said frame, a weigh bucket fulcrumed on one end of said weigh beam, and a counterweight pivotally carried by the other end of said weigh beam; means for varying the effective weight of said counterweight and including a relatively long flexible

weighing chain having one end dependably fastened to said counterweight, means for supporting said chain in a pendant loop and for varying the length of said pendant loop, said last named means including a vertically disposed housing adapted to receive the other end of said chain and having a sprocket gear engageable with said chain and journaled adjacent the upper end thereof, and means for positively imparting a movement of rotation to said sprocket gear to thereby propel the chain from said housing or to retract the chain into said housing and vary the length of the pendant loop thereof:

12. In a weighing scale wherein is provided a frame; a weigh beam fulcrumed on said frame; a weigh bucket fulcrumed on one end of said weigh beam; and a counterweight pivotally carried by the other end of said weigh beam; means for varying the effective weight of said counterweight and including a relatively long flexible weighing chain having one end dependably fastened to said counterweight, means for supporting said chain in a pendant loop and for varying the length of said pendant loop, said last named means including a vertically disposed housing adapted to receive the other end of said chain and having a sprocket gear engageable with said chain and journaled adjacent the upper end thereof, and means comprising gear and shaft connections extending from the operator's station to said sprocket gear for positively imparting a movement of rotation to said sprocket gear to thereby propel the chain from said housing or to retract the chain into said housing and vary the length of the pendant loop thereof.

13. In a weighing scale wherein is provided a frame, a weigh beam fulcrumed on said frame, a weigh bucket fulcrumed on one end of said weigh beam, and a counterweight pivotally carried by the other end of said weigh beam; means for varying the effective weight of said counterweight and including a relatively long flexible weighing chain having one end dependably fastened to said counterweight, means for supporting said chain in a pendant loop and for varying the length of said pendant loop, said last named means including a vertically disposed housing adapted to receive the other end of said chain and having a sprocket gear engageable with said chain and journaled adjacent the upper end thereof, gear and shaft connections extending from a station remote from said counterweight to said sprocket gear for positively imparting a movement of rotation to said sprocket gear to thereby propel the chain from said housing or to retract the chain into said housing, and means for locking said gear and shaft connections in fixed position.

HOWLAND F. BRIGGS.
